UNITED STATES PATENT OFFICE

165,213

PHOTOGRAPHIC PROCESSING APPARATUS

Guy D. Aydlett, Rochester, N. Y., assignor to Eastman Kodak Company, Rochester, N. Y., a corporation of New Jersey

Application June 14, 1951, Serial No. 15,543

Term of patent 3½ years

(Cl. D61—1)

To all whom it may concern:

Be it known that I, Guy D. Aydlett, a citizen of the United States, residing at Rochester, in the county of Monroe and State of New York, have invented a new, original, and ornamental Design for a Photographic Processing Apparatus of which the following is a specification, reference being had to the accompanying drawings, forming a part thereof, in which:

Fig. 1 is a perspective view of a photographic processing apparatus showing my new design, this view being taken from the upper right hand side so as to show parts of the front, side and top walls;

Fig. 2 is a view similar to Fig. 1 but with a perspective taken from the upper left hand side showing parts of the front, side and top walls; and

Fig. 3 is a rear plan view on a reduced scale of the apparatus shown in the preceding figures.

I claim:

The ornamental design for a photographic processing apparatus, as shown.

GUY D. AYDLETT.
